(57) CLAIM

The ornamental design for a motion detector with audible alarm and remote control therefor, as shown and described.

DESCRIPTION

FIG. 1 is a front elevated view of a motion detector with audible alarm and remote control therefor showing my new design;

FIG. 2 is a rear elevated view of the motion detector with audible alarm and remote control therefor;

FIG. 3 is a side elevated view of the motion detector with audible alarm and remote control therefor; and,

FIG. 4 is a top plan view of the motion detector with audible alarm and remote control therefor, the top plan view being a mirror image of a bottom plan view of the design.
